UNITED STATES PATENT OFFICE.

THOMAS E. McCREEBY, OF WEST PHILADELPHIA, PENNSYLVANIA.

SAFETY RAZOR.

Application filed April 14, 1925. Serial No. 23,014.

This invention relates to improvements in safety razors,—one object of the invention being to so construct the guard member that, by cooperation with the base or clamping member, angular adjustments of the cutting edges of the blade may be enhanced, and so that adjustability of the razor effectively to perform its functions under various conditions may be easily and accurately accomplished to obtain the best results in shaving.

With these and other objects in view, the invention consists in certain novel features as hereinafter set forth and pointed out in the claim.

In the accompanying drawings,—

Figure 1 is a plan view of a safety razor embodying my improvements.

Figure 2 is a view in section on the line 2—2 of Figure 1.

Figure 3 is a view in section on the line 3—3 of Figure 1.

Figure 4 is a separate view of the guard, and

Figures 5 and 6 are views showing modifications.

In the drawings, the base or clamping member is represented at 1 and made with a concave upper face. The base member is provided with upstanding studs or posts 2 between its center and respective ends to pass through suitable holes in the blade 3. A threaded shank 4 projects from the central portion of the base 1 and enters a suitably threaded socket in the lower portion of a handle member 5. Between the blade 3 and the lower end of the handle member, my improved guard is disposed,—the lower end of the handle forming a shoulder 6 to engage the guard and clamp the blade between the same and the base 1, it being understood of course that the blade and guard are provided with central openings for the passage of the threaded shank 4, and it will also be understood that the transverse diameter of the blade is somewhat greater than that of the base 1 and somewhat less than that of the guard.

My improved guard 7 comprises two members 8—9, each formed at its outer edge to provide a comb or guard fingers 10. The members 8—9 comprising the guard 7 are hinged together at their inner edges so that the hinged connection between the guard members shall be substantially coincident with the longitudinal axis of the guard, and

the respective guard members are provided on their inner edges with recesses which cooperate to form openings 11 for the accommodation of the guide studs 2 and an opening 12 for the accommodation of the threaded shank 4. While the hinge portions between the members 8—9 may be constructed in any suitable manner and so as to be either flush with the upper surface of the guard or to project below the lower surface thereof, still I find it convenient to form said hinge connections on the upper surface of the guard. Thus in the drawings, the guard member 8 is provided with a series of lugs 13 having eyes 14 to enter between pairs of eyes 15 projecting from lugs 16 on the guard member 9,—suitable hinge pins being passed through the several sets of intermeshing eyes.

In the embodiment of my invention shown in Figures 1 to 4, the underface of the guard 7 is made convex but if desired this underface of the guard may be made concave as shown in Figure 5 or portions of the guard members may be made flat on their underfaces as shown in Figure 6.

By turning the handle member, the guard will be caused to exert pressure against the thin blade and so bend the latter as to change or adjust the angularity of its cutting edges and at the same time the guard members will turn on their hinge connection with each other so that the comb portions of the guard members will be caused to move in a direction away from the cutting edge portions of the blade, thus rendering the cutting portions of the blade more available for effective service.

In order that the different adjustments of the angularity of the cutting edges of the blade may be accurately ascertained, I provide on the companion members of the guard at the center of the same, a circular scale of figures as indicated at 17 and a mark 18 is provided on the handle member to register with any figure on the scale desired.

Having fully described my invention what I claim as new and desire to secure by Letters-Patent, is:

In a safety razor, the combination of a base member having a concave inner surface, a threaded stud extending from the inner concave surface of the base member, a handle engaged on the stud, and a guard interposed between the handle and the base and receiving pressure directly from the handle

whereby to clamp a razor blade to the base, the guard consisting of two similar members hinged together for free relative movement along their inner edges with said edges extending across and in direct contact with the end of the handle whereby the pressure exerted through the handle will be applied to both members of the guard and thence over

the entire face of the blade to clamp the blade to the base member and will vary the angular relation between the edges of the blade and the outer edges of the guard. 10

In testimony whereof, I have signed this specification.

THOMAS R. McCREERY.
